Primary Examiner — W. A. Teddy Falloway
Assistant Examiner — Amanda Kay Birdwell(57) **CLAIM**

The ornamental design for a bottle, as shown and described.

DESCRIPTION

FIG. 1 is a front view of a bottle showing my new design; FIG. 2 is a left elevational view thereof; FIG. 3 is a right elevational view thereof; FIG. 4 is a rear elevational view thereof; FIG. 5 is a top plan view thereof; FIG. 6 is a bottom plan view thereof; FIG. 7 is a front-top-right elevational view thereof; FIG. 8 is a bottom-rear elevational view thereof; FIG. 9 is a top-rear elevational view thereof; and, FIG. 10 is bottom-front-right elevational view thereof. The broken lines shown illustrate portions of the bottle and form no part of the claimed design.

1 Claim, 10 Drawing Sheets(56)
